US0D1054797S

(12) **United States Design Patent** (10) **Patent No.:** **US D1,054,797 S**
(45) **Date of Patent:** **** Dec. 24, 2024**

(54) **FOOD STORAGE BOX**

(71) Applicant: **Zhongshan Jiabao Daily Necessities Co., Ltd**, Zhongshan (CN)

(72) Inventor: **Shengbin Cai**, Zhongshan (CN)

(73) Assignee: **Zhongshan Jiabao Daily Necessities Co., Ltd**, Zhongshan (CN)

(**) Term: **15 Years**

(21) Appl. No.: **29/949,230**

(22) Filed: **Jun. 26, 2024**

(51) LOC (14) Cl. **09-07**

(52) U.S. Cl.

CLAIM

The ornamental design for a food storage box, as shown and described.

DESCRIPTION

FIG. 1 is a front, right and top perspective view of a food storage box, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the food storage box that form no part of the claimed design.

1 Claim, 8 Drawing Sheets
